BERNARDO ORDOÑEZ, OF CORDOBA, ARGENTINA.

MICROMETRIC SPACER FOR TYPE-WRITING MACHINES.

1,262,094.

Specification of Letters Patent. Patented Oct. 24, 1916.

Application filed November 19, 1912, Serial No. 732,247. Renewed March 17, 1916. Serial No. 84,951.

To all whom it may concern:

Be it known that I, BERNARDO ORDOÑEZ, a citizen of Argentina, residing at Cordoba, in the Province of Cordoba, Argentina, have invented a new and Improved 5 Micrometric Spacer for Type-Writing Machines, of which the following is a full, clear, and exact description.

The object of the invention is to provide 10 a new and improved micrometric spacer for typewriting machines, arranged to enable the operator to quickly and accurately set the platen-turning mechanism for producing any desired distance between succeeding 15 lines of the written matter, also enabling the operator to accurately follow ruled paper without being obliged to turn the platen by hand.

In order to accomplish the desired result 20 use is made of a wheel rotating with the cylindrical platen of the typewriting machine, a manually-controlled gripping device adapted to engage the rim of the said wheel to turn the latter, and an adjustable 25 regulating device for increasing or decreasing the throw of the said gripping device according to the distance between successive lines.

A practical embodiment of the invention 30 is represented in the accompanying drawings forming a part of this specification, in which similar characters of reference indicate corresponding parts in all the views.

Figure 1 is a plan view of the micrometric spacer as applied to an Underwood typewriting machine; Fig. 2 is an enlarged elevation of the left-hand end of the same, parts being in section; Fig. 3 is a cross section of the same on the line 6—6 of Fig. 4; Fig. 4 is a plan view of the same, parts being broken out; Fig. 5 is a sectional front elevation of the same on the line 5—5 of Fig. 2; Fig. 6 is a cross section of the same on the line 6—6 of Fig. 4; Fig. 7 is a sectional side elevation of the 45 brake mechanism for the cylindrical platen; Fig. 8 is an enlarged plan view of the micrometric adjustment; Fig. 9 is a perspective view of the cam operating lever; and Fig. 10 is an end view of the same.

The Underwood typewriting machine on 50 which the micrometric spacer is shown applied is of the usual construction so that a detailed description of the machine is not deemed necessary, it being sufficient to state 55 that the shaft A carrying the cylindrical platen B is journaled in the usual bearings

C' of the platen frame C adapted to be raised and lowered on the carriage for upper and lower case type by the usual rock arms D engaging studs E arranged on the platen frame C.

On the platen shaft A is secured or formed a wheel F having a rim F' adapted to be engaged at the inner surface by a gripping shoe or block G' formed on or secured to a gripping arm G fulcrumed at G² on a covering plate H for the inner face of the wheel F. The covering plate H is provided with a pin H' (see Figs. 4 and 6) engaged by one end of a spring I coiled 70 around and attached to the bearing C' on the platen frame C. The covering plate H is loose on the platen shaft A and is under tension exerted by the spring I.

The gripping arm G is adapted to be 75 engaged by a cam arm J fulcrumed at J' on the covering plate H and the free end of the cam arm J is adapted to be engaged by a shoulder K' (see Fig. 3) formed on the fulcrum end of a lever K loosely fulcrumed on the platen shaft A. The inner portion of the lever K as well as the arms G and J are arranged within the opening of the wheel F and the upper end K² of the lever K is bent to one side and extends through a cut-out portion in the covering plate H, as plainly indicated in Fig. 6. The outer free end of the lever K is pivotally connected by a link L with a slide N 80 extending transversely and mounted to slide in suitable bearings arranged on the platen frame C. The forward end of the slide N is provided with an angular lug N' engaged by an arm O mounted to turn on a stud O' carried by the carriage, and on the arm O 85 is secured a handle O² adapted to be taken hold of by the operator to impart a swinging motion to the arm O with a view to giving a transverse sliding movement to the slide N. On moving the slide N rearwardly the 90 link L imparts a swinging motion to the lever K to rock the latter so that the shoulder K' thereof swings the cam arm J outward whereby a like outward swinging movement is given to the gripping arm G 95 which by its gripping block G' now engages the inner surface of the flange F' to rotate the wheel F. As the wheel F is secured on the platen shaft A it is evident that the platen shaft A is turned and with it 100 the cylindrical platen B. The gripping block G' is normally out of engagement 105

with the rim F' of the wheel F but is in close proximity thereto so that it requires but very little movement to move the gripping block G' in gripping contact with the rim F' . Thus, on starting the handle O^2 in the direction of the arrow a' (see Figs. 1 and 4) the gripping block G' is engaged with the rim F' and during the remainder of the movement given to the handle O^2 in 10 the direction of the arrow a' the wheel F is turned in the direction of the arrow b' and with it the cylindrical platen B . It is understood that the pressure exerted by the shoulder K' of the working lever K on the 15 free end of the cam arm J not only causes the said arm J to swing slightly outward for gripping purposes, but also carries the said arm J along, thus turning the covering plate H in the direction of the arrow b' 20 against the tension of its spring I .

When the handle O^2 is released the block G' releases its grip on the rim F' of the wheel F and the spring I pressing the covering plate H returns the latter to normal position and with it the arms G and J pivoted on the said covering plate H . It will also be noticed that the return movement of the cam lever J causes a return rocking of the lever K whereby the link I imparts a return sliding movement to the slide N and thus returns the arm O and the handle O^2 to normal position. By reference to Fig. 3, it will be noticed that the cam arm J engages the gripping arm G at the free end thereof, 30 and the free end of the cam arm J is engaged by the lug K' of the oscillating lever K so that an exceedingly powerful action is had to swing the gripping arm G outward at the time the handle O^2 is started, to insure 35 a firm, positive gripping of the block G' with the rim F' of the wheel F . The forward rocking movement given to the covering plate H and the arms G and J carried thereby is limited and for this purpose the plate H is provided with a stop lug H^2 40 adapted to move in contact with the stud E at the left-hand side of the machine. The return movement of the covering plate H is limited by the lug H^2 abutting against the lower end of a vertical screw rod P screwing in the top of the platen frame C and provided at its upper end with a head P' 45 adapted to be taken hold of by the operator for turning the screw rod P so as to screw the same up or down to increase or decrease the throw of the covering plate H and the arms G and J carried thereby.

In order to indicate the amount of the throw given to the wheel F , use is made of 60 an indicator arranged as follows: On the covering plate H is secured a pointer H^3 extending over the peripheral face of the wheel F (see Fig. 8) and indicating on a segment H^4 fixed on the left-hand side of the platen frame C , the segment being provided

with a graduation representing linear measurement, the zero mark being rearmost, so that the distance from zero to the pointer H^3 indicates the amount of throw given to the wheel F and platen B at each operation. 70

In order to indicate micrometric adjustment when screwing the screw rod P up or down, use is made of a pointer P^2 which is attached to the screw rod head P' , and depends from the same to indicate on a graduated link P^3 attached to the top of the platen frame C . The circular graduation on the disk P^3 represents linear measurement, and the total length indicated corresponds to the distance between adjacent marks of the 80 graduation on the segment H^4 , so that on one complete turn of the screw rod P the pointer P^2 makes a complete turn on the disk P^3 while the pointer H^3 moves from one mark of the graduation on the segment H^4 85 to the next following one.

By the arrangement described, the user of the machine can see at a glance the amount of the throw to which the device has been set, and when turning the screw rod P the 90 user can accurately set the device to any desired throw on watching the movement of the pointers H^3 and P^2 .

From the foregoing it will be seen that by adjusting the screw P a minute adjustment can be had relative to the throw given to the platen B for each movement of the handle O^2 from the left to the right to turn the platen B the desired distance with a view to space succeeding lines the desired distance 100 apart. After the screw rod P has been adjusted it is locked in place by a lock nut P^4 screwing on the screw rod P against the upper face of the disk P^3 .

It will be noticed that when the parts are 105 in normal dormant position the platen B can be turned by hand as the spacing mechanism is then practically completely free of the platen. It will further be noticed that by the arrangement described the most minute adjustment can be had relative to the 110 distance between successive lines by adjusting the screw P correspondingly.

In order to prevent the platen B from 115 being shifted too far owing to the momentum given to the platen while turning it, use is made of a brake shoe Q engaging the peripheral face of the rim F' of the wheel F . The brake shoe Q is held on a brake lever Q' fulcrumed at Q^2 on the platen frame C , and the said brake lever Q' is pressed on by a spring Q^3 to hold the brake shoe Q in frictional contact with the peripheral face of the rim F' . On the rear end of the brake lever Q' is journaled a shaft Q^4 carrying a 125 cam wheel Q^5 in contact at its peripheral face with the inclined plate C' forming part of the platen frame C (see Figs. 2, 3 and 7). On the shaft Q^4 is also secured a handle Q^6 under the control of the operator for turning 130

the shaft Q⁴ so as to release the cam wheel Q⁵ relative to the inclined surface C'. By the arrangement described the brake lever can be swung out of action whenever it is desired to freely turn the platen B.

5 Although the line-spacing device is shown applied to an Underwood typewriting machine, it is clearly evident that the device can be used on other makes of typewriting machines.

10 Having thus described my invention, I claim as new and desire to secure by Letters Patent:

1. A line-spacing device for the platen of typewriting machines, comprising a wheel 15 rotating with the platen, a gripping device adapted to engage the inside of the said wheel, a spring pressing the said gripping device to hold the latter normally out of 20 engagement with the said wheel, a fixed stop, an adjustable stop, the stops limiting the forward and return movement of the said gripping device, and manually-controlled means for actuating the said gripping device.

2. A line-spacing device for typewriting machines, comprising a wheel rotating with the platen, a spring pressed plate loose on the shaft of the platen, a gripping arm fulcrumed on the said plate and adapted to engage the inside of the wheel, a cam arm for 30 engaging the gripping arm, and manually controlled means for operating the cam arm.

3. A line-spacing device for the platen of typewriting machines, comprising a wheel 35 rotating with the platen, a spring-pressed plate loose on the platen shaft, a gripping arm fulcrumed on the said plate and adapted to engage the inside of the rim of 40 the said wheel, a cam arm fulcrumed on the said plate and adapted to engage the said gripping arm, an actuating lever fulcrumed loosely on the platen shaft and adapted to engage the said cam arm, and 45 manually-controlled means connected with the said actuating lever.

4. A line-spacing device for the platen of typewriting machines, comprising a wheel 50 rotating with the platen, a spring-pressed plate loose on the platen shaft, a gripping arm fulcrumed on the said plate and adapted to engage the inside of the rim of 55 the said wheel, a cam arm fulcrumed on the said plate and adapted to engage the said gripping arm, an actuating lever fulcrumed loosely on the platen shaft and adapted to engage the said cam arm, a lug 60 fixed on the said plate, a fixed stop for engagement by the said lug when turning the plate forward, an adjustable stop for limiting 65 the return movement of the said plate, and manually controlled means connected with the said actuating lever.

5. A line-spacing device for the platen of typewriting machines, comprising a wheel

70 rotating with the platen, a spring-pressed plate loose on the platen shaft, a gripping arm fulcrumed on the said plate and adapted to engage the inside of the rim of the said wheel, a cam arm fulcrumed on the said plate and adapted to engage the said gripping arm, an actuating lever fulcrumed loosely on the platen shaft and adapted to engage the said cam arm, a slide, a link connecting the slide with the 75 said lever, and a hand lever connected with the said slide.

6. A line-spacing device for the platen of typewriting machines, comprising a wheel 80 rotating with the platen, a spring-pressed plate loose on the platen shaft, a gripping arm fulcrumed on the said plate and adapted to engage the inside of the rim of the said wheel, a cam arm fulcrumed on the said plate and adapted to engage the 85 said gripping arm, an actuating lever fulcrumed loosely on the platen shaft and adapted to engage the said cam arm, means for limiting the forward turning motion of the said plate, adjustable means for limiting 90 the return movement of the said plate, and manually-controlled means connected with the said actuating lever.

7. A line-spacing device for the platen of typewriting machines, comprising a wheel 95 rotating with the platen, a spring-pressed plate loose on the platen shaft, a gripping arm fulcrumed on the said plate and adapted to engage the inside of the rim of the said wheel, a cam arm fulcrumed on 100 the said plate and adapted to engage the said gripping arm, an actuating lever fulcrumed loosely on the platen shaft and provided with a shoulder adapted to engage the face end of the said cam arm, a lug 105 fixed on the said plate, a fixed stop for engagement by the said lug on the forward turning of the plate, a screw rod for engagement by the said lug on the return movement of the said plate, indicating 110 means for indicating the adjustment of the said screw rod, and manually-controlled means connected with the said actuating lever.

8. In a line spacing device for typewriting machines, a flanged wheel rotating with the platen, a spring pressed member loose on the shaft of the platen, a gripping member pivoted to the spring pressed member and adapted to engage the inner face of the 120 flange of the said wheel, a cam also pivoted on the spring pressed member and adapted to engage the gripping member to swing it into engagement with the flange of the wheel, a sliding member, and means operated by the sliding member for operating 125 the cam.

9. In a line spacing device for typewriting machines, a flanged wheel rotating with the platen, a spring pressed member loose 130

- on the shaft of the platen, a gripping member pivoted to the spring pressed member and adapted to engage the inner face of the flange of the wheel, a cam also pivoted to 5 the spring pressed member and adapted to swing the cam into engagement with the flange of the wheel, a member loosely fulcrumed on the platen shaft and adapted to engage the cam, a sliding member, and a 10 pivoted connection between the sliding member and the member loosely fulcrumed on the platen shaft.
10. In a line-spacing device for typewriting machines, a flanged wheel rotating with 15 the platen, a spring pressed plate loose on the shaft of the platen, a gripping arm pivoted to said plate and having a shoe adapted to engage the inner surface of the flange of the wheel, a cam arm pivoted to 20 the said plate and adapted to engage the gripping arm, a lever loosely fulcrumed on the platen shaft and provided with a shoulder adapted to engage the free end of the cam arm, said lever extending out 25 through the flange of the wheel, a manually operated slide and a link connecting the slide with the lever.
11. In a line-spacing device for typewriting machines, a wheel rotating with the 30 platen, a spring pressed member loose on the shaft of the platen and provided with

a projection, a manually controlled gripping device carried by the said member adapted to engage the wheel to turn the same, a stop with which the projection of the 35 member engages when said member turns in one direction, a graduated plate, a screw passing through the graduated plate and adapted to engage the projection of the said member, and a pointer carried by said 40 screw.

12. A line-spacing device for typewriting machines, comprising a wheel rotating with the cylindrical platen of the machine, a manually controlled slide, a fixed stop, an 45 adjustable stop, and a spring-pressed mechanism controlled by the said slide and adapted to engage the said wheel to rotate the latter on imparting movement to the slide, the return movement of the said mechanism being caused by the spring, the said mechanism being provided with a projection adapted to engage the fixed stop and with which the adjustable stop normally 50 engages.

In testimony whereof I have signed my name to this specification in the presence of two subscribing witnesses.

BERNARDO ORDOÑEZ.
